Patented Nov. 30, 1915.

UNITED STATES PATENT OFFICE.

GEORGE P. KUNDA, OF CENTERVILLE, IOWA.

TRACK STRUCTURE.

1,162,082.

Specification of Letters Patent. Patented Nov. 30, 1915.

Application filed June 21, 1915. Serial No. 35,362.

To all whom it may concern:

Be it known that I, GEORGE P. KUNDA, a citizen of the United States, residing at Centerville, in the county of Appanoose and State of Iowa, have invented certain new and useful Improvements in Track Structures, of which the following is a specification, reference being had to the accompanying drawings.

10 My present invention relates to new and useful improvements in track structures and as its principal object aims to improve the construction of the rails at crossings and switches, in such manner that it will not be necessary to employ bolts or the like in connecting the meeting terminals of the rail sections.

Another object of the invention is to provide a novel arrangement of the ties at the 20 crossing or switch, the ties being connected to each other in pairs by the rods.

The above, and other incidental objects of a similar nature, which will be hereinafter more specifically treated are accomplished by such means as are illustrated in the accompanying drawings, described in the following specification, and then more particularly pointed out in the claim which is appended hereto and forms part of this 30 application.

With reference to the drawings, wherein there has been illustrated the preferred embodiment of this invention, as it is reduced to practice, and throughout the several 35 views of which similar reference numerals designate corresponding parts, Figure 1 is a plan view; Fig. 2 is a detail perspective view of the preferred form of rail joint employed in connection with the track structure.

40 In the accompanying drawings, the numerals 10 and 11 designate generally the two rails of the main track and the numerals 12 and 13 designate the rails of the siding track. These rails are mounted upon ties, indicated at 14. As disclosed best in Fig. 1, the ties are, at the portion of the track whereat the siding runs into the crossing, arranged in pairs, the individual ties of each 45 pair being connected to each other by means of rods 15, on the terminals of which are threaded the nuts 16. Spacing blocks or struts, indicated at 17 are disposed between the ties for an obvious purpose. The rail 12 50 of the siding is formed as an integral part

of the section 18 of the main track rail 11, as best disclosed in Fig. 1. The other rail 13 of the siding is formed as an integral part of the section 19 of the main track rail 11. Extending between the sections 18 and 19 of the main track rail 11, are two rail sections 20 and 21. The member 20 is connected to the member 18 by a scarf joint, generally designated by the numeral 22. The member 21 is pivotally connected to the 60 member 20 and, therefore, constitutes a switching point. A similar switching point, indicated at 23 is pivoted to the rail section 24, which forms a part of the siding rail 12.

65 A joint, generally designated by the numeral 25, connects the member 24 to the siding rails 12. This joint 25 is equivalent to the joint 22, which is shown in detail in Fig. 2, to which figure reference will now be had. As shown in this figure the base portion 26 of the rail section A is removed on one side of the web, producing the shoulder 27. The tread portion 28 is cut-away on the opposite side producing the shoulder 29. The other rail section B is provided with 70 the parallel spaced plates 30 and 31, which are adapted to engage against the opposite faces of the web of the rail section A. The lower edge of the plate 30 is spaced above the bottom face of the rail base, so that it 75 may engage upon the upper face of the rail base of the section A. The upper edge of the plate 31 is beveled, as at 32 so that it may flatly engage against the beveled lower face of the head of the rail section A. It 80 has been found that the above described rail joint, shown in Fig. 2, is particularly efficient in a rail structure of the present type and I, therefore, desire to employ it in preference to other types of rail joints. 85

90 In order that the switching points 21 and 23 may be held in relatively fixed relation to each other, yet may be capable of slight movement when a train is passing through the switch, I provide the rods 36 which are 100 of relatively light steel and are capable of being longitudinally flexed, under the thrust of the passing train. These rods 36 are provided with the laterally offset studs 37, which pass through the members 21 and 23 105 and are pivotally secured against withdrawal therefrom.

95 The main rail 10 is made up adjacent to the switch by three sections 38, 39 and 40 which are connected to each other by means 110

of joints 41 and 42, equivalent to the joints 22 and 23, which are as previously explained, illustrated in detail in Fig. 2.

From the foregoing description, it will now be observed that it is not necessary in the present invention to employ any bolts or equivalent fastening elements in properly connecting the terminals of the rail sections of the different tracks and that the cost of 10 the track structure is, therefore, materially reduced. It will also be noted that by connecting the ties in pairs, in the manner shown in Fig. 1 particularly, there is less liability of slippage of the ties either longitudinally or transversely, than in the ordinary track. In this connection, it will be apparent that whereas in the ordinary track, if a tie becomes loose or the foundation material beneath it is unduly crushed and permits the tie to be undermined, the tie may then slip transversely or longitudinally on the road bed. In the present invention, however, the loosening of one tie will not result in the consequent movement of this tie for no single tie, of any of the pairs of ties can move unless it carries with it the other tie.

In reduction to practice, it has been found that the form of this invention illustrated in the drawings and referred to in the above 30 description as the preferred embodiment is the most efficient and practical; yet realizing that the conditions concurrent with the adoption of this device will necessarily vary,

it is desirable to emphasize the fact that various minor changes in the details of construction, proportion and arrangement of parts may be resorted to, when required, without sacrificing any of the advantages of this invention, as defined by the appended claim.

What is claimed is:—

In a rail joint, a pair of meeting rail ends, the first of said rail ends having its base portion removed on one side of the web and having its tread portion removed on the 45 opposite side of the web, the other of said rail terminals being provided with parallel spaced plates adapted to engage against opposite faces of the web of the first rail end, the lower edge of one of said plates being 50 adapted to seat upon the base of the first rail terminal, and to have its upper edge contiguous with the tread surface of the first rail, the other plate being beveled to engage against the lower face of the tread of the 55 first rail, the base of the second rail and being continuous along the lower edge of the second mentioned plate member and being adapted to form a continuation of the rail base of the first rail terminal.

In testimony whereof I hereunto affix my signature in the presence of two witnesses.

GEORGE P. KUNDA.
